(57) **CLAIM**

The ornamental design for the television stand, as shown and described.

DESCRIPTION

FIG. 1 is a perspective view of the television stand from the front, showing a TV disposed on the stand;

FIG. 2 is a perspective view of the television stand from the rear, showing a TV disposed on the stand;

FIG. 3 is a top plan view of the television stand;

FIG. 4 is a bottom plan view of the television stand;

FIG. 5 is a rear elevational view of the television stand;

FIG. 6 is a front elevational view of the television stand; and,

FIG. 7 is a side elevational view of the television stand.

The broken lines shown are for illustrative purposes only and form no part of the claimed design.
